AUGUSTA POSTELLA MCKAY, OF ROME, GEORGIA, ASSIGNOR TO TOWERS & SULLIVAN
MANUFACTURING COMPANY, OF ROME, GEORGIA, A CORPORATION OF GEORGIA.

DISK PLOW AND FRAME FOR SAME.

Application filed May 17, 1926. Serial No. 109,685.

The present invention relates to improvements in disk plows, and has for an object to provide an improved plow frame constructed and arranged with reference to the wheel supports and disk mountings as to secure improved strength and resistance to the 5 torsional strains set up incident to the use of the disk plows, and whereby also an effective distribution of the weight is had to oppose the tilting tendency in the frame resulting from the reaction of the disks upon 10 the soil.

Another object of the invention is to provide improved means for the raising and 15 lowering of the plow with particular reference to the operator who, under present day practice, is seated upon a tractor used for drawing the plow. Under this practice it becomes necessary that the raising and lowering device be within easy reach of the 20 tractor seat at all times, and this for many reasons is impracticable with the well known system of levers now in general use.

The invention also contemplates certain 25 improved constructional parts in the plow frame, steering mechanism and disk mountings, whereby ease in operation, great strength and economy in production are secured.

30 With the foregoing and other objects in view, the invention will be more fully described hereinafter, and will be more particularly pointed out in the claims appended hereto.

35 In the drawings, wherein like symbols refer to like or corresponding parts throughout the several views,

Figure 1 is a perspective view of an improved disk plow constructed according to 40 the present invention.

Figure 2 is a top plan view of the same.

Figure 3 is an enlarged front view of the raising and lowering handle and adjacent parts.

45 Figure 4 is a fragmentary longitudinal section taken on the line 4-4 in Figure 3.

Figure 5 is a front elevation of the spring support for the raising and lowering device.

50 Figure 6 is a cross section taken on the line 6-6 in Figure 2.

Figure 7 is a similar section taken on the line 7-7 in Figure 2.

Figure 8 is also a cross section taken on the line 8-8 in Figure 2.

Figure 9 is a front elevation of the disk 55 support.

Figure 10 is a cross section, with parts shown in elevation, taken through the guide lever and support for the raising and lowering mechanism.

Figure 11 is a fragmentary elevation, with parts shown in section, of the movable stand of the raising and lowering device, and

Figure 12 is a section taken on the line 12-12 in Figure 11.

Referring more particularly to the drawings, 14 designates an elongated narrow bar forming the front portion of the frame and being reinforced by the central upstanding rib 15, which terminates short in the enlarged head 16 of the bar to which is pivoted as on the fulcrum 17 a bell crank lever 18 carrying the clevis 19 for attachment to the draw bar of a tractor.

The clevis 19 is carried forwardly of the head 16 by one branch arm of the bell crank lever 18; while the lateral branch of this bell crank lever is pivotally coupled to an end of a link 20 extending back along and above the neck bar 14 and preferably being 80 twisted at some point intermediate its ends to strengthen the bar and to enable it to be made of thin strap metal. This metal is therefore enabled to lie along side the lever 21 to which it is attached as by the bolt 22. The lever is bolted at its lower end as by the bolt 23 to the web or reinforcing rib 15 of the neck bar 14. This construction is shown in Figure 10, wherein the neck bar is shown to be of channel construction having 85 downwardly extending side flanges 24 and 25. These flanges are therefore offset from the reinforcing rib 15, which extends upwardly from approximately the central portion of the neck bar. The lever 21 is adapted to swing about the bolt 23 and for this purpose a flanged bushing 26 is fitted about the bolt 23 and in an opening in the lower end of the lever 21. In a similar way the link 20 is fitted to the bolt 22 passing 100 through the lever 21 at a point above its lower end by a similar flanged bushing 27.

The lever 21 swings back and forth in a plane coincident with the direction of move-

ment of the machine or the longitudinal center line thereof, and the lever carries a spring-pressed latch 28 under the control of a hand grip 29. The latch is adapted to fit in the teeth of a segmental rack bar 30. By gripping the handle or upper end of the lever 21 the hand grip 29 may be at the same time squeezed in the hand and the latch 28 withdrawn from the segmental rack 30 to enable the lever to be swung about its fulcrum point 23 and consequently through the link 20 to adjust the clevis. The rack bar 30 is bolted to the web or rib 15.

The web 15 intersects a flange 31 and extends to and joins with a companion flange 32. The flanges 31 and 32 are curved in form and spaced apart and they stand up at the opposite edges of the curved frame member or casting 33. The casting 33 originates approximately at the rear end of the neck bar 14, and the neck bar is widened at this rear portion where it merges into the flange 31 and casting and the flange 31 extends completely across the wider rear end portion of the neck bar 14 in a sweeping curve and it is curved to the forward end of the inner flange 32. The inner flange is preferably higher and the flanges are joined and reinforced by the rear portion of the web or rib 15. These flanges and the casting are further reinforced by the transverse webs 34, 35 and 36. At its rear end the inner flange 32 is flared wider and it extends at substantially right angles to form the tail flange 37 to which is joined the rear end of the outer flange 31, such rear end of the outer flange being directed inwardly to meet the tail flange 37. From this point of junction the tail flange 37 is directed rearwardly in substantially the direction of movement of the machine, and an apron 38 extends outwardly from this tail flange 37 joining at its forward end to the inwardly directed end portion of the outer flange 31.

The casting extends in an arc to one side of the neck bar 14 and at its ends it is provided with the spaced and substantially parallel supports 39 and 40, which lie diagonally with respect to the longitudinal axis 50 of the frame. These supports or hangers 39 and 40 are adapted to carry the disk plows 41 and 42 and these plows are mounted for rotation upon the pins 43 shown in Figure 8. The pins and their bushings 44 are mounted in tapered sockets 45 carried at the lower portion of plates 46, shown in Figure 9, which plates are provided with the openings 47 for the attaching bolts 48, which pass through the supports or hangers 39 and 40. The plates have their lower ends reduced and bent outwardly to give the disks the proper inclination. The plates 46 are further provided with the enlargements 49 and 50 along their opposite vertical edges 65 and at the inner sides of the plates 46 are

the horizontally extending shoulders 51, which take beneath the supports or hangers 39 and 40, as shown in Figure 8.

The disks 41 and 42 are shown as spaced both longitudinally and laterally and they are offset diagonally in accordance with the usual practice. The curved frame is constructed with a view to meeting the resistance and the reaction set up by disk plows so arranged and disposed as will be later explained.

The rear plow support or hanger 40 is provided with a leg 52 substantially parallel to the rearmost portion of the tail rib 37, and the tail rib and the leg 52 join with opposite enlarged ends of the sleeve 53. The axle 54 is received through this sleeve, as shown in Figure 6, and bolts 55 in any suitable number are passed through the axle and sleeve to support the axle and avoid its rotation. The axle carries the ground wheel 56. The other ground wheel 57 is offset rearwardly from the companion ground wheel 56 and is carried in a supplemental frame 58 having the arms 59 and 60, which are fitted to rotate about the axle 54 at opposite ends of the sleeve 53. The bolts 55 passing through the sleeve also serve to hold the supplemental frame 58 against longitudinal or axial motion on the axle 54. The rear portion of the supplemental frame 58 carries the tubular bearing 61 in which is fitted the stub shaft 62 for carrying the ground wheel 57. The shaft is preferably held in the tubular bearing and against motion by use of the bolt 63.

The supplemental frame 58 is provided with an upstanding web 64 at its outer side to which is coupled as by bolts or other suitable means a post 65 useful for swinging the supplemental frame about the axle 54 and thus adjusting the depth of the disk plows. The wheel 57 carried by this adjustable frame tracks in rear of the rearmost disk plow 42, while the weight wheel 56 is at the outer end of the elongated axle 54 and is spaced from the frame and from the disks. Any number of weights may be fitted to this wheel or its axle in accordance with prevailing practice. The post 65, shown in Figures 1, 11 and 12 extends upwardly from the web 64 of the supplemental frame and is passed through a yoke 66 provided with an opening to receive the post and having the upstanding arms 67 and 68 perforated near their upper free ends to receive trunnions 69 and 70 upon the swivel nut 71 through which the screw rod 72 is threaded. A collar 73 is fitted about the post 65 above the yoke 66 and is secured to the post as by the cotter pin 74. The post projects above the collar 73 and receives at its upper end an opening in the U-shaped brace 75, the arms of which are secured as by the rivets 76 and 77 to the side 130

bars 67 and 68 of the yoke. The yoke carrying the swivel nut 71 is thus free to turn on the post 65. In other words the yoke is swivelly mounted about a vertical axis and the nut 71 is swivelly mounted in the yoke 5 about a horizontal axis. This permits the yoke and nut to accommodate itself to changes in positions of the parts to which they are connected.

10 The screw rod 72 extends forwardly above the disks and at its forward end into and through a shell or casing 78 having lateral trunnions 79 mounted in the arms 80 of a yoke 81 similar to the yoke 66. This yoke is 15 mounted for movement about the vertical axis of the standard 82 and it is supported on the standard by means of the collar 83 pinned to the standard and engaged at its upper end by the U-shaped brace 84 riveted 20 to the side arms 80 of the yoke 81. This construction is shown in Figure 10. The shell 78 is thus permitted to move universally about both vertical and horizontal axes. The shell and its associated parts are 25 shown more particularly in Figures 3, 4 and 5.

In Figure 4 particularly the shell is shown as being contracted at its end 85 to provide 30 an internal shoulder for the series of anti-friction balls 86. A collar 87 takes against these balls at the opposite end and this collar is secured by the pin 88, or otherwise 35 to the screw shaft 72. A second series of balls 89 is mounted against the opposite side of the collar 87 to take up the end thrust 40 of the screw rod. The latter balls 89 are confined by a sleeve 90 fitted about the screw rod 72 and having an outer plate 91 extending 45 against the flange 92 on the forward end of the shell 78 and affixed to this flange 92 as by the countersunk bolts 93. The plate 91 is provided with the forwardly extending 50 rim 94 having a number of notches 95 therein. These notches are shown to divide 55 the rim 94 into quadrants, or in other words 60 to be located at 90 degrees apart; but any number of notches may be provided.

These notches are arranged to cooperate 55 with a dog 96 upon an operating lever 97, 60 which is provided with the forwardly extending handle 98 for purposes of rotation. The lever 97 is provided with the elongated slot 99, as shown in Figure 3 to straddle the collar 100 of the device shown in Figure 5. 65 This device is a spring support or spring backer and it is secured to the screw rod 72 by the use of a pin 101, which also extends outwardly and through the lever 97 in order 70 to form a rocking joint for the lever 97 to enable the lever to rock the dog 96 into and 75 out of engagement with the notches 95. A coil spring 102 acts to hold the dog 96 in one of the notches 95 and this coil spring is seated in a socket 103 in the end of the lever 80 85 97 opposite the handle 98. The spring 102

engages about a stud 104 on an arm 105 forming part of the spring support or backer. The arm 105 extends radially from the collar 100 and the boss 104 extends through the coil spring 102 and partially into the 70 socket 103.

In operation of the invention, it is to be understood that the disk plow is in reality a turning plow, but all other turning plows are provided with a landside, the functions 75 of which are:—

First, to support the plow share against depressing stresses, thereby assuring a furrow of uniform depth;

Second, to support the plow share against 80 the lateral pressure of the moldboard, thereby securing uniformity in the width of furrows. The landside also relieves the plow frame, or beams, of excessive side thrusts, 85 which result from obstructions being encountered by the angular portions of the plow share and the moldboard.

The disk plow has no landside. Therefore, all side thrusts and depressing strains, 90 together with the torsional stresses resulting 95 therefrom must be borne by the plow frame, because the wheels function as landsides, and the strains described above must be transmitted to the wheels through the medium of the plow frame and the axles. Thus it will be seen that rigidity is one of the most essential qualities of the disk plow frame.

Until quite recently, the idea prevailed among disk plow designers that it was necessary to make each plow a self contained unit 100 so far as its supporting wheels were concerned, that is to say that each plow was provided with three wheels regardless of the number of disks carried, and these wheels were arranged so that after the 105 plow had made its first cut around a land and started on the second round, the front wheel ran in the furrow previously cut by the rear disk, thus serving as a landside in its relations to the front disk. The rear 110 wheel running in the furrow behind the rear disk, functioned as a landside in relation to the rear disk, while the third wheel ran out on the unplowed land and served to balance the plow in an upright position. 115

In the above described cases, the plows were connected to the tractor by means of a more or less flexible hitch, which did not support any part of the weight of the plow, nor receive any of the strains described above, its only function being that of a draft mechanism. 120

In the present type of two wheel disk plows, to which the invention appertains, 125 the front wheel has been eliminated, as has also the flexible hitch, the main frame of the plow being projected forward so as to form a rigid draft mechanism, which in addition to serving as a draft mechanism, supports 130 a portion of the weight of the plow and

takes its pro rata of the depressing strains and side thrusts; but since this draft mechanism is connected to the tractor draw bar by means of a short toggle or pivotal connection, it does not take its pro rata of the torsional strains, these being transmitted to the plow wheels through the medium of the plow frame and axles.

It has been proven by conclusive experiments that any appreciable amount of resiliency in the frame of this type of plow will permit the disk to bob up and down in the ground, which is due to the absence of a front wheel to furnish a close-up support for the front disk. This bobbing motion of the disks is accentuated by the rear wheel dropping into the low places and then rising to mount the high places left in the bottom of the furrow as a result of the disks bobbing up and down, and eventually this bobbing develops into an undulating motion, which causes the plow to rise and fall like a small boat riding heavy waves.

It will be noted that the trouble described above is not due to the plow crossing small ridges on the surface of the ground. In fact this trouble is less apparent when crossing a continued series of small ridges than when plowing on an apparently smooth surface. It seems that a series of small ridges has a tendency to break the sway of this undulating motion, which becomes more or less uniform on smooth surfaces and especially in soft ground.

The above described trouble, in addition to causing unsatisfactory work, soon results in undue wear and elongation of bolts and rivets when these are used to assemble a plow frame which is composed of a multiplicity of parts, and it is obvious that a plow of this type will not work at all if permitted to become shakily.

For these and many other reasons well known to those in this art the rigidity is probably the most important factor in the frame of a plow of this type. The rigidity with relation to torsional strains is especially important.

It will be noted that when the disks are raised out of the ground, the weight of the plow is supported at three points, namely, at the hitch 19, wheel 56 and wheel 57. When the disks are lowered into the ground and the plow starts forward, there is a backward pressure and a side thrust and a downward pressure against the lower cutting edges of the disks at points P and Q.

Owing to the fact that the front disk 41, together with its supporting bracket, is projected beyond an imaginary line of support which runs along line X, Y, Figure 1, this imaginary line of support becomes the actual line of support. The weight of the plow together with the resisting forces already described now rests upon the hitch 19 and

the wheel 57; while the wheel 56 acts as ballast to prevent the plow frame toppling over toward the side of the frame upon which the disks are supported. It has become an established custom among disk plow manufacturers of this particular type of plow to furnish, as regular equipment, a set of weights, to be bolted onto the wheel 56, to serve as ballast for the purpose described; which emphasizes the necessity of great strength and rigidity in the cross sections of the frame of this type of plow.

It will be seen that the combination of forces described above, namely, the backward and downward pressure and the side thrust developed by the disks, operating against the lower edges of the disks, will be resolved into a torsional strain, which is transmitted to the plow frame at point A and distributed in a longitudinal direction along the dotted line A—B and line C—B, crossing the line of support at point L and terminating near the point of ballast at B. These torsional strains acting on the lines indicated show the necessity for the heavy flanges 32 and 37. These flanges, together with the ribs, which connect them with flange 31 at the numerous points shown, reinforce this line of torsional stress and make for a very high degree of rigidity in the plow frame.

Moreover the main line of support X—Y is greatly reinforced against resiliency by means of the flange 32 and the rib 15, both of which are again reinforced by means of the flange 31 which extends on both sides of the rib 15 or in other words intersects this rib.

The construction described does away with the necessity for a front wheel and also avoids any bobbing up and down of the plows, particularly the front disk 41 which is the most difficult to control.

The raising and lowering device is operated solely through the handle 98 which is at all times accessible to the driver upon the seat of the tractor in front. This handle is rotated and is disengaged from its locking mechanism by pulling forwardly upon the handle 98, so that the operation may be achieved by one hand while the other is left free for the control of the steering mechanism and other necessary operations on the tractor. The rotary handle 98 has been developed because of the difficulty encountered with the lever system of control. The lever is difficult of access because it swings wide and without the reach of the operator on the tractor seat and the lever apparatus is difficult to operate in hard soils. With the stop arrangement the crank handle may be instantaneously stopped and secured in any desired position and it will therefore yield a nice adjustment.

In Figure 7 the flanges 31 and 32 are shown as extending below the plane of the

beam or curved frame member 33. The lower flanges extend in the same plane as the upper flanges 31 and 32 and thus the beam is composed of three elongated narrow strips, two of which, namely, the flanges 31 and 32 are disposed at right angles to the third strip, namely, the beam 33.

The elongated flanges will resist torsional stresses as these stresses are opposed by the great depth of the flanges. In other words the stresses are received edgewise and not flatwise of the flanges. The draft strains are received edgewise of the beam 33 and thus great resistance is opposed to any tendency to straighten the curved beam or to subject it to breakage.

It is obvious that various changes and modifications may be made in the details of construction and design of the above specifically described embodiment of this invention without departing from the spirit thereof, such changes and modifications being restricted only by the scope of the following claims:—

25 What is claimed is:—

1. A disk plow comprising an elongated narrow neck bar, a reinforcing rib extending lengthwise of said neck bar, a curved beam made in one piece with said neck bar and extending rearwardly and laterally thereof, said beam having spaced upstanding flanges at its edges, the outermost flange intersecting said rib of the neck bar, the inner flange receiving thereagainst the end of the rib, supports for disk plows at the ends of said curved beam, and supporting wheels for the rear portion of the beam.

2. A disk plow comprising an elongated narrow neck bar, a reinforcing rib extending lengthwise of said neck bar, a curved beam joined at its front end with the rear

end of said neck bar, said beam having spaced flanges at its edges, the outermost flange extending around the forward end of the beam and intersecting said rib of the neck bar, supports for disk plows extending from said curved beam, and supporting wheels for the rear portion of the beam.

3. An integral plow frame having a neck bar and a curved beam extending rearwardly and laterally thereof, said beam having spaced upstanding flanges at its edges and said neck bar having a reinforcing rib extending lengthwise of said neck bar and intersecting the outermost flange of said beam and terminating against the inner flange thereof, said rib having means forwardly and rearwardly of said outer flange for supporting a rack bar and also having means between said first means and forwardly of said outer flange for pivotally supporting a lever to traverse said rack bar, said neck bar having at its outer end and in line with said rib means for coupling the neck bar to a draft device.

4. An integral frame for disk plows and the like having a neck bar provided with a lengthwise extending reinforcing rib, and a curved frame member extending from the rear end of the neck bar, said curved member having spaced upstanding flanges and spaced substantially radially disposed reinforcing means between the flanges, the rib of the neck bar admitting the forward portion of the inner flange of the curved member, and the outer flange of said member being arched forwardly around the forward end of the member and intersecting the rib to interbrace the rib and flange structure and reinforce the juncture of the neck bar and the curved member.

AUGUSTA POSTELLA MCKAY.
